UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

BIN FRONT.

Application filed January 28, 1922. Serial No. 532,524.

This invention relates in general to shelving, and while the embodiment of it, selected for the purposes of illustration, is a bin front, it will be readily manifest that it has 5 other and different uses, as for example in a downturned shelf edge.

A principal object of the present invention is the provision of an improved construction in bin fronts and the like for holding a plurality of labels which may be provided without the addition of material, and without involving the performance of costly operations in the manufacture of the shelving.

15 The invention has for a further object the provision of a label holding construction in bin fronts, shelf edges and the like, into which the labels may be easily and expeditiously inserted and removed and which will, 20 by reason of its construction, firmly hold the labels in place.

Another important object of the invention is the provision of a bin front wherein the labels may be positioned and protected 25 against soiling in use.

Numerous other objects and advantages of the invention will be apparent as the same is better understood from the following description, which, taken in connection with 30 the accompanying drawings, discloses a preferred embodiment thereof.

Referring to the drawings,

Figure 1 is a front elevation of a bin front provided with my present invention, and 35 showing the same in position in a shelving organization; and

Figs. 2 and 3 are sections taken substantially on the lines 2—2 and 3—3 of Fig. 1.

A portion of a shelving organization is 40 shown on the drawing and comprises vertical uprights 11 of tubular form. These uprights support an appropriate arrangement of cross bearers 12 on which rest shelves 13.

45 Reference character 14 indicates a bin front, i. e., a member adapted to be disposed between two adjacent front uprights and above a shelf to provide the front wall of a bin, the remaining walls being provided by the shelving proper. This bin front, in 50 the present instance, is secured to the uprights by tongue members 15 secured to each end of the bin front at 16 and interlocking with the uprights themselves. The bin front 55 consists of a metal sheet having a top hori-

zontal flange 17 and a bottom horizontal flange 18, these flanges being formed by bending the material on horizontal lines of bend 19 to cause the flanges to extend outwardly to provide a guard and then bending them inwardly on lines of bend 21 to provide return flange portions or retaining flanges. It is not to be understood that this order of bending is the procedure preferably adopted, the terms above mentioned being merely that 60 of description of the finished structure shown.

At intervals I stamp out portions 22 to provide label holders. Oppositely curved severing lines 23 are cut through the material, the ends of these lines of severance being spaced apart to provide connecting tongues 24 between the sheet body and the set off portions. The portions 22 are in the stamping or pressing arranged in a plane 70 slightly in front of the forward face of the body of the sheet, and the curved lines 23 are preferably of circular form. This construction permits the label edge 25 to be engaged between the portion 22 and the sheet body. In the present instance I have shown a number of portions 22 arranged for the reception of a number of labels, one less than the number of portions 22. The labels may be inserted by first positioning one edge of a label 75 beneath a side of a portion 22 and then snapping the opposite edge between the next adjacent label holding clamp or portion 22. Thus constructed, the label is firmly held in place back within the flanges 21, which protect it from soiling, and above a lowermost flange which under all conditions can act 80 to prevent the label falling or sliding down out of its holder.

It will be noted that the flanges 17 and 18 are themselves label holding flanges. However, it frequently happens (particularly where bin dividers are used) that a number of labels of relatively short length are desired and the portions 22 act to restrain such 90 short labels against sidewise movement, holding them accurately in predetermined relation.

It is thought that the invention and many of its attendant advantages will be understood from the foregoing description, and it will be apparent that various changes may be made in the form, construction and arrangement of the parts without departing 105 from the spirit and scope of the invention 110

or sacrificing all of its material advantages, the form hereinbefore described being merely a preferred embodiment thereof.

I claim:

5. 1. The combination of, spaced uprights, means cooperating with said uprights to provide a bin, and a bin front, said bin front comprising, a body part adapted for interlocking engagement between the spaced uprights and having a plurality of portions defined by lines of severance and pressed bodily away from the plane of the body part forming retaining buttons adapted to embrace opposite edges of a label having characters thereon for referring to the contents of the bin.

2. The combination of, spaced uprights, means cooperating with said uprights to provide a bin, and a bin front, said bin front comprising, a body part adapted for interlocking engagement between the spaced uprights, a plurality of portions of the body being defined by lines of severance spaced from each other at their ends to provide connecting links, a part of each portion being defined by curved lines and pressed bodily away from the plane of the body to provide retaining buttons adapted to receive and hold the edges of a plurality of labels.

3. The combination of, spaced uprights, means cooperating with said uprights to provide a bin, and a bin front, said bin front comprising, a body adapted to engage be-

tween the spaced uprights having a portion formed along an edge thereof to provide a card retaining slot, and portions upset from the plane of the body at a distance from the edge, adapted to engage opposite edges of labels.

4. The combination of, spaced uprights, means cooperating with said uprights to provide a bin, and a bin front, said bin front comprising, a body adapted to engage between spaced uprights having a plurality of opposite edge portions formed to provide a card retaining slot, and portions upset from the plane of the body and interrupting the slot for embracing opposite edges of a card arranged to refer to the contents of the bin.

5. The combination of, spaced uprights, means cooperating with said uprights to provide a bin, and a bin front, said bin front comprising, a body formed to provide top and bottom label retaining flanges, and brackets removably attached to said body for supporting the body between the spaced uprights, said body having a plurality of projections struck up from the material thereof, intermediate the top and bottom retaining flanges, and intermediate the ends of the body, for cooperating with the top and bottom retaining flanges to secure a plurality of labels against movement in either direction.

WALTER N. VANCE.
